(57)

CLAIM

The ornamental design for a cooking pan as shown and described.

DESCRIPTION

3. Cooking pan
 7. Cooking pan
 3.1 Perspective
 3.2 Top
 3.3 Bottom
 3.4 Left
 3.5 Right
 3.6 Front
 3.7 Back
 7.1 Perspective
 7.2 Top
 7.3 Bottom
 7.4 Left
 7.5 Right
 7.6 Front
 7.7 Back

1 Claim, 14 Drawing Sheets
